(57) **CLAIM**

We claim the ornamental design for a battery boot, as shown and described.

DESCRIPTION

FIG. 1 is a perspective view of our battery boot design;

FIG. 2 is a side elevation view of thereof;

FIG. 3 is a side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown represent unclaimed subject matter and form no part of the claimed design.

1 Claim, 7 Drawing Sheets(56)
